UNITED STATES PATENT OFFICE.

FREDERICK JACOBY, OF FORT WAYNE, INDIANA.

ICE-BOX.

SPECIFICATION forming part of Letters Patent No. 271,072, dated January 23, 1883.

Application filed August 29, 1882. (No model.)

To all whom it may concern:
Be it known that I, FREDERICK JACOBY, of Fort Wayne, in the county of Allen, and in the State of Indiana, have invented certain new and useful Improvements in Ice-Boxes; and I do hereby declare that the following is a full, clear, and exact description thereof, reference being had to the accompanying drawings, and to the letters of reference marked thereon, 10 making a part of this specification.

This invention has for its objects to provide an improved ice-box or refrigerator which is especially designed for the use of butchers and other dealers in perishable articles, in which 15 such articles may be kept in bulk, as well as in smaller quantities for retail purposes, and which can be readily and conveniently cleaned when necessary, which will permit the escape of foul and damp air, and which will prevent 20 the escape of cold air when opened for retailing articles.

In the drawings, Figure 1 represents a vertical sectional view on the line $x x$ of Fig. 3. Fig. 2 represents a sectional view on the line 25 $y y$ of Fig. 3. Fig. 3 represents a top view of the improved ice-box or refrigerator, and Fig. 4 a vertical cross-section of the slatted platform in detail.

The letter A indicates the body of the refrigerator, which in the present instance consists of a rectangular box constructed with double walls, as usual.

The letter B indicates a platform, supported in the box by means of the beams C in such 35 manner as to leave a space between its sides and the walls of the box. The platform consists of two slatted metallic sections, D' and D'', hinged together at one edge. The sections consist of slats V-shaped in cross-section, 40 the said slats having spaces between them, and the upper slats being inverted and directly over the spaces between the slats of the lower section, so as to shed the water from the melting ice into the lower sections, from which it 45 is conducted off by means of a perforated tube, E', and pipe F'.

The letter B' indicates a flooring, composed of spaced slats mounted on beams B'', supported upon the platform upon which the ice rests. 50 The letter E indicates a series of inclined slatted sections—four in number—which form

an inclosure above the flooring, in order to retain the ice. The said sections are removable, the top beam of each, at the ends, being adapted to fit in the blocks F, secured to the interior of the refrigerator, the blocks being provided with recesses G for the reception of the beams. The sections rest at their lower edges on the top of the platform. 55

The letter K indicates a funnel-shaped tube 60 extending through the top of the box. The said tube has secured to its lower end a concavo-convex disk, L, and below this, to the inside of the top of the refrigerator, is secured a concavo convex perforated plate, M. Within 65 the disk M, I place a layer of sponge, which I saturate with a liquid made from chloride of calcium, the object being to attract the moisture from the air about the surface of the ice, and thus render it dry, and consequently cooler. 70 The perforations in the disk M admit the moisture to the saturated sponge, and the unperforated disk L serves the purpose of concentrating it near the lower end of the tube K, and the said tube serves to admit the external 75 air to the surface of the saturated sponge. The said sponge having become exceedingly moist by the continued absorption of the vapor in the air immediately around the ice, the external air admitted to the sponge, as above 80 indicated, being less moist than the sponge, naturally takes up a considerable quantity of moisture in the latter, and this process being naturally continuous, it virtually results in effecting an exhaust from the air in the ice 85 chamber or box, rendering said air dry, and consequently cooler, and therefore better adapted for the purpose of refrigeration.

It is observable that I contemplate freeing the sponge of the excess of accumulated moisture by squeezing or otherwise should the external air fail to remove it as rapidly as collected; but this will not be frequently necessary, as by the means above described I am able to remove the moisture nearly, if not 95 quite, as fast as collected in the sponge.

The letter N indicates two tubes leading from the bottom of the box to near the top, where they are provided with short pipes O, extending outward through the sides of the 100 refrigerator. The pipes near their lower ends are provided with hoods P, which terminate a

slight distance above the floor at their lower edges, and the pipes communicate with the interior of said hoods by means of perforations R. These pipes serve to carry off the foul air from the lower part of the refrigerator. At one end of the refrigerator is located, on the inside, a box or compartment, S. This is provided with a slanting hinged top, T, which, when raised, throws the interior of the box into communication with the interior of the refrigerator, so as to admit cold air to the said box. The refrigerator has an opening, U, at one side, which leads into the box S. This opening is provided with a vertically-sliding door, V, which may be glazed, if desired. The sliding door is connected with the hinged top of the box T by means of a cord passing over a pulley, W, in such manner that when the sliding door is closed the hinged top is opened, and vice versa, thus permitting perishable articles to be retailed without the loss of any considerable amount of cold air and without permitting heated air to enter the refrigerator proper. The top of the refrigerator is hinged to the body, so that it can be raised in order to remove the parts for cleaning, and the said top is provided with an opening and cover, Y, for the insertion of ice. The refrigerator at one side is provided with a door, Z, by means of which large articles—such as quarters of animals, &c.—may be carried into the refrigerator.

Having thus described my invention, what I claim, and desire to secure by Letters Patent, is—

1. The combination, in an ice-box, of the hinged slatted sections supported upon cross-

beams having slats V-shaped in cross-section, and arranged to shed the water from the upper into the lower slats, and provided with collecting and discharging tubes, with the slatted ice-flooring, and the series of inclined ice-inclosing sections resting upon the said flooring and supported by cross-beams, substantially as shown and described.

2. In combination with the refrigerator having the hinged tops, provided with the door or hatchway for filling in the ice, the slatted flooring, the inclined inclosing-sections, and the hinged metallic sections and discharge-pipes for guiding, receiving, and discharging the drippings, the whole being arranged as shown and described.

3. In combination with the refrigerator, the pipe leading through the top and provided with a concavo-convex disk at its inner end, and the concavo-convex perforated plate located below said disk, substantially as and for the purposes set forth.

4. In an ice-box, the combination, with the lid, of a tube for admitting air, a concavo-convex imperforated disk secured to the tube, and a concavo-convex perforated disk secured to the lid, and forming a chamber which is adapted to receive a moisture-absorbent, substantially as shown and described.

In testimony whereof I affix my signature, in presence of two witnesses, this 26th day of June, 1882.

FR. JACOBY.
